UNITED STATES PATENT OFFICE.

WILLIAM J. RAMSAIER, OF NEW YORK, N. Y.

PRINTING-PRESS.

1,239,128.

Specification of Letters Patent.

Patented Sept. 4, 1917.

Application filed July 29, 1916. Serial No. 111,999.

To all whom it may concern:

Be it known that I, WILLIAM J. RAMSAIER, a citizen of the United States, and resident of the borough of Manhattan, city, 5 county, and State of New York, have invented certain new and useful Improvements in Printing-Presses, of which the following is a specification.

This invention relates to improvements in 10 that class of printing presses in which the type or printing surface is held on a bed and the printing platen is carried by a rocking bridge. The inking rollers are mounted in a carriage which is normally at 15 the top of the type bed and is moved down across the face of the printing surface and back to its normal position while the bridge and the printing platen are moved away from the type bed. This type of press is 20 generally known as the universal platen printing press. The invention is applicable to any form of press with a rocker bridge and a printing platen carried thereby.

One of the main objects of this invention 25 is to simplify and improve the means whereby the inking roller carriage will be actuated from the platen-carrying bridge, or the mechanism connected to and operating therewith.

Another object of the invention is to provide means whereby the inking roller carriage actuating mechanism may be disconnected 30 from the platen-carrying bridge through the operation of the throw-off bar.

Another object of the invention is to provide means whereby when the throw-off bar 35 is returned to its normal position, the inking roller carriage will be again connected to its actuating mechanism.

There are other important objects and advantages of the invention which will fully 40 hereinafter appear.

In the drawings, Figure 1 is a vertical 45 sectional view of the press, the inking roller carriage and the printing platen being shown in side elevation;

Fig. 2 a vertical sectional view of the 50 platen-carrying bridge, on the line II-II of Fig. 1, a portion of the mechanism being broken away to more clearly show the construction;

Fig. 3 a horizontal sectional view of the 55 press on the line III-III of Fig. 1;

Fig. 4 a detail rear view of the cams 60 which operate to connect and disconnect the

inking roller carriage from the rocking bridge, the operating link being shown in sectional view;

Fig. 5 a sectional view taken on the line 60 V-V of Fig. 4;

Fig. 6 a horizontal sectional view taken on the line VI-VI of Fig. 4;

Fig. 7 a detail side elevation of the means 65 for disconnecting the inking roller carriage mechanism from the actuating mechanism connected to the rocking bridge; and

Fig. 8 a detail rear view of the mechanism shown in Fig. 7;

Referring to the various parts by numerals, 1 designates the main driving shaft 70 which may be rotated in any suitable manner and from any suitable source of power. On this shaft is secured a disk 2 which carries a crank pin 3. On this pin is mounted the rear end of a forwardly extending 75 bridge-operating link 4. The shaft 1 carries a second disk similar to disk 2, and to this disk is connected another link 4, the forward ends of said links being connected to the opposite ends of the platen-carrying 80 bridge 5.

The platen-carrying bridge is formed with curved rockers 6 which bear on horizontal tracks 7 located in the forward upper part of the machine frame. The bridge 85 is formed with forwardly and downwardly extending side plates 8 which carry, at their forward ends, inwardly extending lugs 9, said lugs being adapted to engage and slide on the tracks 7 when the printing platen is 90 completing its inward printing movement. The printing platen 10 is supported at the inner side of the bridge and is adapted to be brought into close proximity with the forward face of the type bed 11, as shown 95 in Fig. 1, when the bridge is at the end of its inward movement. The bridge is guided in its rocking movement by the slotted cam guide 5^a, as shown clearly in Fig. 1 and as is well known in this class of presses. When 100 the bridge has been moved forwardly a sufficient distance to free the lugs 9 from the tracks 7, the bridge will be rocked forwardly and downwardly, bringing the printing platen to an inclined position and permitting the removal of the printed sheet 105 and the proper adjustment of the new sheet to be printed.

The cam guide 5^a carries a downwardly extending bracket 12, said cam and bracket 110

being bolted to the under side of the bridge. In the lower end of this bracket is mounted a horizontal bar 13. On this bar is rotatably mounted an eccentric 14, said eccentric being formed with a forwardly extending substantially horizontal arm 15. On the eccentric is mounted a sleeve 16 to which is rigidly connected a downwardly extending operating bar 17. Pivoted on a 10 horizontal bar 18 is a bell crank lever 19, one arm of which extends forwardly and downwardly and is connected to the lower end of the bar 17, the other arm extending upwardly and forwardly and being connected at its upper end to the upwardly and rearwardly extending operating-hook 20. It is obvious from the foregoing that as the bridge is rocked forwardly and downwardly, the bar 17 will be raised and the 15 operating-hook thrown upwardly and rearwardly by means of the lever 19; and upon the reverse motion of the rocking bridge the operating-hook will be drawn forwardly and downwardly.

25 At the rear of the machine, above the rear end of the operating-hook, is mounted a transverse rock shaft 21. To the ends of this rock shaft are secured upwardly and forwardly extending crank arms 22, whose upper ends are connected by links 23 to the roller carriage 24. The rock shaft 21 is also provided with two short, downwardly and forwardly extending arms 25, said arms being placed a suitable distance on each 30 side of the middle of said shaft, as shown clearly in Figs. 3 and 8. The lower ends of these arms are connected by a pin 26, on which are mounted three rollers 27, 27^a and 28, the locking roller 28 being located 35 between the two supporting rollers 27 and 27^a, as shown clearly in Fig. 8. The operating hook 20 is formed with a slot 29 which runs, for a portion of its length, substantially parallel with the longitudinal line of 40 the said hook. Near its rear end this slot is inclined downwardly and rearwardly, and at the forward end of this inclined portion an upwardly extending portion 30 is formed, said portion 30 being substantially 45 perpendicular to the main body of the slot, as shown clearly in Figs. 1 and 7. The locking roller 28, in the normal operation of the machine, rests in the portion 30 of the slot of the operating hook, as shown 50 clearly in Fig. 1, the parts then being in their normal locked and operative position. It is manifest that as the operating-hook is reciprocated, the rock shaft 21 will be 55 rotated and the inking roller carriage moved down over the printing surface and then back to its normal position above the platen.

60 Whenever it may be desired to disconnect the operating-hook from the inking roller carriage it is only necessary to lift the operating hook 20 sufficiently to release the 65

locking roller 28 from the portion 30 of the slot of the operating-hook. For this purpose I provide the following mechanism, and adapt the same to be operated from the platen throw-off bar.

70 The throw-off bar 31 is mounted on the upper ends of arms 32, said arms being connected to and extending radially from eccentric sleeves 33 which surround the bridge trunnions 34, as is usual in presses 75 of this type. Rigidly connected to the throw-off bar and extending downwardly therefrom, is an arm 35, said arm being curved around the forward curved side of the platen-carrying bridge, as shown clearly 80 in Fig. 1. To the lower end of this arm 35 is connected a link 36, the lower end of which is connected to the forward end of the arm 15. As heretofore described, the arm 15 is connected to the eccentric sleeve 85 14 mounted on the pin 13. By thus connecting the throw-off bar to the eccentric sleeve 14 the variation in the distance between the center of the trunnions 34 and the center of the pivot 17^a at the lower end 90 of the operating bar when the throw-off is operated, is automatically compensated for. When the throw-off bar is moved forwardly and downwardly the bridge is moved forwardly through the eccentric sleeves 33. This slightly increases the distance between 95 the center of the pivot 17^a and the center of the trunnions 34, and this slight increase in distance must be compensated for in order to prevent a partial operation of the 100 inking roller carriage. As the movements of this carriage and all of its operating mechanism are carefully timed, it is essential that the proper operative relations be maintained when the throw-off bar is operated. The throw-off bar is released by 105 means of the cams 37, said cams being operated through the bar 38 as is usual in devices of this kind.

110 Mounted on the operating bar 17 is a sliding head 39. The bar 17 is formed with two slots 40, and in said slots are mounted blocks 41, said blocks being connected to the sliding head by means of transverse pins 42, so that the head will be accurately 115 guided in its vertical movement. Connected to the sliding head is a link 43, the upper end of which is connected to the forwardly extending arm 15 of the sleeve 14, whereby the sliding head will be vertically 120 reciprocated through the operation of the throw-off bar. On one side of the sliding head is formed an inclined cam 44, said cam extending upwardly and forwardly from the rear edge of the head. On the opposite 125 side of the sliding head is formed a cam 45, said cam extending downwardly and forwardly from the rear edge of the sliding head, as indicated clearly in Figs. 1 and 5 of the drawings. These cams 44 and 45 are 130

adapted to engage the forward ends of horizontally movable bars 46 and 47, cam 44 being adapted to engage bar 46, and cam 45 being adapted to engage bar 47. The forward ends of these bars are provided with suitable antifriction rollers, as indicated in Fig. 1; and said bars are mounted to slide in a bearing 48 in the machine frame. At the rear of the machine frame, below the 10 operating hook, is mounted a transverse bearing rod 49, and on this rod is pivotally mounted a hook-releasing device 50. This device is formed with two upwardly extending arms 51, between which fits the 15 operating hook 20, as shown clearly in Fig. 8. A lifting roller 52 is mounted between said arms 51 and is adapted to engage the lower edge of the operating hook and lift it sufficiently to free the locking roller 28 20 from the portion 30 of the slot 29 in said hook. On the upper ends of the arms 51 are formed curved supporting flanges 53, which are adapted to fit under and engage the supporting rollers 27 and 27^a when the 25 operating hook has been released from the roller 28, as shown clearly in Fig. 7. When the parts are in this position the entire weight of the inking roller carriage and its operating parts is supported through the 30 arms 51, the cross bar 49 and the machine frame. It is manifest, therefore, that it will be unnecessary to provide any counterbalancing weight to support the inking roller carriage when said carriage operating mechanism 35 is disconnected from the rocking bridge. The rear end of the bar 46 is connected to the releasing device below the pivot thereof, and the rear end of the bar 47 is connected to the releasing device at a 40 point above its pivot, as shown clearly in Figs. 1 and 8 of the drawings.

As shown in Fig. 1 of the drawings, the bar 47 is adapted to be engaged by the cam 45 when the sliding head 39 is moved downwardly through the action of the throw-off bar. The rearward movement of the bar 47 throws upwardly the releasing device, thereby elevating the rear end of the operating hook and bringing the rollers 27 and 27^a 45 to rest on the flanges 53, thereby disconnecting the inking roller carriage from the operating mechanism. It is manifest that as the bar 47 is moved rearwardly the bar 46 will be thrown forwardly into the path of its actuating cam 44, so that when the sliding head is elevated by the return of the throw-off bar to its normal position said bar 46 will be engaged by its cam 44 and forced rearwardly. This operation will move the 50 releasing device forward and permit the hook to drop and bring the portion 30 of the slot 29 in position to receive the roller 28. It is manifest from the foregoing that the inking roller carriage will be rendered 55 inoperative when the throw-off bar is moved

forwardly and downwardly; and that it will be automatically rendered operative when the throw-off bar is moved back to its normal position. The mechanism for releasing the operating hook from the locking roller 70 28 and for permitting the operating hook to drop into engagement with said locking roller, constitutes what might be properly termed a "make-and-break device" in the mechanism for operating the inking roller 75 carriage, that is to say, these devices form means by which the said mechanism may be rendered operative or inoperative by making or breaking the operative connection between the bridge and the inking roller carriage. 80

It is frequently desirable to maintain the inking roller carriage operatively connected to the rocking bridge when the throw-off bar has been operated, in order that the ink 85 may be rolled a number of times over the printing surface before an impression is taken. To accomplish this I secure the cam 45 on a plate 54, said plate being pivoted at 90 55 on the sliding head and formed with a slot 56 adapted to receive a clamping nut 59 mounted on a threaded bolt 58, as shown clearly in Figs. 5 and 6 of the drawings. By loosening the clamping nut 57 the plate 54 may be moved downwardly, thereby withdrawing the cam 45 from the path of the arm 47. In this position of the parts the bars 46 and 47 will not be operated during the vertical reciprocation of the sliding head 39, and therefore the releasing device will remain inactive and the operating hook will remain in 95 operative connection with the roller 28. The plate 54, when released, will be dropped down to a stop pin 57 on the sliding head. 100

The inking roller carriage shown in Fig. 105 1, forms the subject-matter of another application for Letters Patent, and will not, therefore, be described herein.

What I claim is:

1. A printing press comprising a printing 110 bed, an inking roller carriage, a bridge, means for rocking said bridge, means for connecting the bridge to the inking roller carriage, whereby the said carriage will be moved through the operation of the bridge, a throw-off mechanism connected to the bridge for rendering the printing platen inoperative, a compensating means operated by said throw-off mechanism and automatically maintaining the proper operative relation between the bridge and the carriage operating means, and means operated through the compensating means for disconnecting the bridge from the inking roller carriage when the throw-off mechanism is 115 120 operated. 125

2. A printing press comprising a bridge, means for rocking said bridge, a throw-off mechanism, an inking roller carriage, operative means connecting said carriage to the 130

bridge, means for disconnecting the bridge from the inking roller carriage, a movable cam for operating said carriage disconnecting means, and means connecting said cam to the throw-off mechanism whereby the movement of said cam will be controlled through said throw-off mechanism.

3. A printing press comprising an inking roller carriage, a bridge, means for rocking the bridge, an operating rod connected to the bridge and adapted to be moved vertically as the bridge is rocked, operating means connecting the said rod to the inking roller carriage whereby the rocking of the bridge will move said carriage, means for disconnecting the roller carriage from the operating mechanism, a sliding head mounted on the operating rod, means carried by said head for actuating the carriage disconnecting means, a throw-off mechanism, and means connecting the sliding head to said throw-off mechanism.

4. A printing press comprising a bridge, means for rocking said bridge, an inking roller carriage, a throw-off mechanism connected to the bridge, means for connecting and disconnecting the bridge and the inking roller carriage, a pair of movable cams for operating the said connecting and disconnecting means, and means operatively connecting said cams to the throw-off mechanism whereby the inking roller carriage will be rendered inoperative when the throw-off mechanism is operated, and will be rendered operative when the throw-off mechanism is returned to its normal inoperative position.

5. A printing press comprising a bridge, means for rocking said bridge, a throw-off mechanism, an inking roller carriage, operative means for connecting said carriage to the bridge, a pair of reciprocal rods, means operated by said rods for connecting and disconnecting the bridge and the inking roller carriage, means for operating one of said rods to disconnect the bridge and the inking roller carriage when the throw-off mechanism is operated, and means for operating the other rod to connect the bridge and the inking roller carriage when the throw-off mechanism is returned to its normal inoperative position.

6. A printing press comprising a bridge, means for rocking said bridge, a throw-off mechanism, an inking roller carriage, operative means for connecting said carriage to the bridge, a pair of reciprocal rods, means operated by said rods for connecting and disconnecting the bridge and the inking roller carriage, a cam for operating one of said rods to disconnect the bridge and the inking roller carriage when the throw-off mechanism is operated, a cam for operating the other rod to connect the bridge and the inking roller carriage when the throw-off

mechanism is returned to its normal inoperative position, and means for connecting said cams to the throw-off mechanism.

7. A printing press comprising an inking roller carriage, a bridge, means for rocking the bridge for the printing operation, means operatively connecting the bridge to the inking roller carriage whereby said carriage will be moved for the inking operation through the movement of the bridge, a throw-off mechanism connected to the bridge for rendering the bridge inoperative for the printing operation, and means operated by the throw-off mechanism for disconnecting the bridge from the inking roller carriage, said disconnecting means supporting the carriage when said carriage is disconnected from the bridge.

8. A printing press comprising an inking roller carriage, a rocking bridge, a depending rod connected to said bridge, a crank arm connected to the lower end of said rod, an operating-hook connected to said crank arm, means connecting said operating-hook to the inking roller carriage, and means to disconnect the operating-hook from the inking roller carriage, said means serving to support said operating hook and the said carriage in their disconnected positions.

9. A printing press comprising an inking roller carriage, a rocking bridge, a depending rod connected to said bridge, a crank arm connected to the lower end of said rod, an operating-hook connected to said crank arm, means connecting said operating hook to the inking roller carriage, a throw-off mechanism connected to the bridge, and means operated by said throw-off mechanism to disconnect the operating-hook from the inking roller carriage and to support said hook and said carriage when said throw-off mechanism is operated, said means operating to connect the said operating-hook to the inking roller carriage mechanism when the throw-off is returned to its normal inoperative position.

10. A printing press comprising a printing bed, an inking roller carriage, a bridge, means for rocking the bridge, an operating rod connected to the bridge and adapted to be moved vertically as the bridge is rocked, operating means connecting the said rod to the inking roller carriage whereby the rocking of the bridge will move said carriage, means for disconnecting the roller carriage from the operating mechanism, a sliding head mounted on the operating rod, means carried by said head for actuating the carriage disconnecting means, a throw-off mechanism, means connecting the sliding head to said throw-off mechanism, and adjustable means for rendering inoperative the said disconnecting means.

11. A printing press comprising a bridge,

means for rocking said bridge, a throw-off mechanism, an inking roller carriage, operative means for connecting said carriage to the bridge, a pair of reciprocable rods, 5 means operated by said rods for connecting and disconnecting the bridge and the inking roller carriage, a cam for operating one of said rods to disconnect the bridge and the inking roller carriage when the throw-off 10 mechanism is operated, said cam being adjustable out of the path of said rod whereby the disconnecting means may be rendered inoperative, a cam for operating the other rod to connect the bridge and the inking roller carriage when the throw-off mechanism is returned to its normal inoperative position, and means for connecting said cams to the throw-off mechanism.

12. A printing press comprising a bridge, 20 means for rocking said bridge, a throw-off mechanism, an inking roller carriage, operative means for connecting said carriage to the bridge, a pair of reciprocable rods, means operated by said rods for connecting 25 and disconnecting the bridge and the inking roller carriage, a sliding head, a cam carried by said head and adapted to operate one of said rods to disconnect the bridge and the inking roller carriage when the throw-off 30 mechanism is operated, said cam being adjustable out of the path of said rod whereby the disconnecting means may be rendered inoperative, a cam for operating the other rod to connect the bridge and the inking roller 35 carriage when the throw-off mechanism is returned to its normal inoperative position, and means for connecting said cams to the throw-off mechanism.

13. A printing press comprising an inking 40 roller carriage, a bridge, means for rocking the bridge, an operating rod connected to the bridge, operating means connecting the said rod to the inking roller carriage, a pair of reciprocable rods, means operated by said 45 rods for connecting and disconnecting the bridge and the inking roller carriage, a sliding head mounted on the operating rod, a cam mounted on said head and adapted to operate one of said rods to disconnect the 50 bridge and the inking roller carriage when the throw-off mechanism is operative, said cam being adjustable out of the path of said rod, whereby the disconnecting means may be rendered inoperative, a cam on said sliding 55 head for operating the other rod to connect the bridge and the inking roller carriage when the throw-off mechanism is returned to its normal inoperative position, and means for connecting the sliding head 60 to the throw-off mechanism.

14. A printing press comprising an inking 65 roller carriage, a bridge, a reciprocable operating-hook, a rock shaft, upwardly and forwardly extending crank arms connected to said shaft, links connecting said crank

arms to the inking roller carriage, downwardly extending arms carried by said rock shaft, a pin connecting said arms, a roller mounted on said pin and adapted to be engaged by the operating-hook, a pair of supporting rollers on said pin on opposite sides of the roller engaged by the operating-hook, a hook-releasing device, a lifting roller carried thereby and adapted to engage the lower edge of the operating-hook, supporting 70 flanges on the upper end of said hook-releasing device and adapted to engage the supporting rollers on opposite sides of the operating-hook, and means for moving the hook-releasing device. 80

15. A printing press comprising an inking roller carriage, a bridge, a reciprocable operating-hook, a rock shaft, upwardly and forwardly extending crank arms connected to said shaft, links connecting said crank 85 arms to the inking roller carriage, downwardly extending arms carried by said rock shaft, a pin connecting said arms, a locking roller on said pin and adapted to be engaged by the operating-hook, a pair of supporting rollers on said pin on opposite sides of the locking roller, a pivoted hook-releasing device, a lifting roller carried thereby and adapted to engage the lower edge of the operating-hook, curved supporting flanges 90 on the upper end of said hook-releasing device and adapted to engage the supporting rollers on opposite sides of the operating-hook, a pair of reciprocable rods connected to the hook-releasing device, one of said rods 100 being adapted to move the hook-releasing device to free the operating-hook from the locking roller and to bring the supporting flanges directly under the supporting rollers, the other rod being adapted to move the 105 hook-releasing device to permit the hook to engage the locking roller, a throw-off mechanism connected to the bridge, and means operated by said throw-off mechanism to move the reciprocable rods. 110

16. A printing press comprising an inking roller carriage, means for moving said carriage, a bridge, means for rocking the bridge, a depending rod connected to said bridge, a crank arm connected to said rod, a reciprocating lever normally connecting said crank arm with the carriage-moving means to impart movement to the carriage when the bridge is rocked, a throw-off mechanism, and means operated by said throw-off mechanism 115 for disconnecting said lever from the carriage moving means. 120

17. A printing press comprising an inking roller carriage, means for moving said carriage, a bridge, means for rocking the 125 bridge, a reciprocable member normally connecting said bridge-rocking means and said carriage-moving means to actuate the carriage when the bridge is rocked, a throw-off mechanism, and means operated by said 130

- throw-off mechanism for shifting said reciprocable member out of its normal path to disconnect the carriage-moving means from the bridge-rocking means.
5. 18. A printing press comprising an inking roller carriage, means for moving said carriage, a bridge, means for rocking the bridge, a reciprocable member normally connecting said bridge-rocking means and said carriage-moving means to actuate the carriage when the bridge is rocked, a throw-off mechanism, means operated by said throw-off mechanism for shifting said reciprocable member out of its normal path to disconnect the carriage-moving means from the bridge-rocking means, and means for supporting said carriage when the carriage is disconnected.
- 10 19. A printing press comprising an inking

roller carriage, means for moving said carriage, a bridge, means for rocking the bridge, a reciprocable member normally connecting said bridge-rocking means and said carriage-moving means to actuate the carriage when the bridge is rocked, a throw-off mechanism, means operated by said throw-off mechanism for shifting said reciprocable member out of its normal path to disconnect the carriage-moving means from the bridge-rocking means, and adjustable means for rendering the throw-off mechanism inoperative to shift said reciprocable connecting member.

In testimony whereof I hereunto affix my signature.

WILLIAM J. RAMSAIER.
